US0D1104385S

(12) **United States Design Patent** (10) **Patent No.:** **US D1,104,385 S**
(45) **Date of Patent:** **** Dec. 2, 2025**

(54) **VACUUM CLEANER FLOOR TOOL**

(71) Applicant: **Emerson Electric Co.**, St. Louis, MO (US)

(72) Inventors: **Christopher Burch**, St. Louis, MO (US); **Liam McGreal**, St. Charles, MO (US); **Matthew A. Williams**, Bridgeton, MO (US); **Devdatta Namdev Shingate**, Pune (IN); **Narendra Gokulsingh Patil**, Pune (IN); **Rahul Shrihari Doke**, Pune (IN); **Bo Shi**, Olivette, MO (US); **Douglas C. Schultz**, Glen Carbon, IL (US)

(73) Assignee: **Emerson Electric Co.**, St. Louis, MO (US)

(**) Term: **15 Years**

(21) Appl. No.: **29/920,035**

(22) Filed: **Dec. 7, 2023**

(51) LOC (15) Cl. **15-05**

(52) U.S. Cl. **USPC D32/31**

(58) **Field of Classification Search**

(57) **CLAIM**

The ornamental design for a vacuum cleaner floor tool as shown and described.

DESCRIPTION

FIG. 1 is a perspective view of a vacuum cleaner floor tool according to the new design.

FIG. 2 is another perspective view thereof.

FIG. 3 is a front view thereof.

FIG. 4 is a rear view thereof.

FIG. 5 is a top view thereof.

FIG. 6 is bottom view thereof.

FIG. 7 is a left-side view thereof; and,

FIG. 8 is a right-side view thereof.

The broken lines in the drawings depict portions of the vacuum cleaner accessory tool and form no part of the claimed design.

1 Claim, 6 Drawing Sheets
